UNITED STATES PATENT OFFICE.

EDDIE ERICKSON, OF DE LAMERE, NORTH DAKOTA.

TOY.

Application filed June 8, 1928. Serial No. 283,860.

My present invention has reference to a toy milch cow.

The object of the invention is the provision of a figure representing a cow and of a figure representing a man for milking the cow, together with motor operated means arranged in the cow figure and which includes crank operated rods movable through the teats of the udder of the cow figure and connected to the hands on the pivoted arms of the figure representing the milker of the cow for imparting a reciprocatory movement to such hands and arms to simulate the milking of the cow.

The drawings which accompany and form part of this application illustrate the improvement.

In the drawings:

Figure 1 is a side elevation of a hollow figure representing a cow with parts broken away and parts in section.

Figure 2 is a transverse sectional view on the line 2-2 of Figure 1.

On a hollow base 1, I mount a hollow figure 2 shaped to represent a cow. Also on the base arranged transversely with respect to the figure 2 and seated on a stool 3 there is a figure 4 representing a person who is supposed to milk the cow. The figure 4 has pivotally connected thereto, as at 5, arms 6', which, of course, merge into hands. Arranged transversely in the hollow figure 1 and finding bearings in the sides thereof there is a winding shaft 6 for a spring motor 7. On the shaft 6 there is a gear 8 which is in mesh with a hollow gear 9. On the gear 9 there is secured a longitudinally extending shaft 10. One end of the shaft 10 finds a bearing in the opening in the rear of the figure and the end

thereof provided with the gear 9 passes 40 through a bearing opening in a transverse plate 11 that is secured to the sides of the hollow figure 1. The shaft 10 has two oppositely directed cranked portions 12 and 13, respectively, and to each of these crank portions there is secured the eye ends of depending rods 14 and 15, respectively. These rods pass through two of the teats 16 of the udder 17 of the cow figure and are fixedly secured to the hand ends of the arms 6'. 50

Manifestly the unwinding of the spring 7 will turn the gear 8 to rotate the gear 9 and consequently the shaft 10. This imparts a reciprocatory movement to the rods 14 and 15 in a vertical direction and a similar movement to the arms 6' on the figure 4 and such movement simulates the milking of a cow. 55

Having described the invention, I claim:

A toy comprising a hollow figure representing a cow, a coil spring having one end secured in the figure, a winding shaft journaled transversely through the figure and to which the second and inner end of the coil spring is secured, a gear on the winding shaft, a second gear in mesh with the first mentioned gear, a longitudinally extending shaft journaled in bearings and secured to the last mentioned gear, said shaft having oppositely disposed cranked portions, a rod loosely secured on each of the cranked portions passing 60 through the teats of the udder of the cow, a second figure arranged transversely with respect to the first mentioned figure and having pivoted arms that merge into hands which are secured to the lower ends of the rods. 65 70 75

In testimony whereof I affix my signature.

EDDIE ERICKSON.
